UNITED STATES PATENT OFFICE.

EMERICK W. CRISPELL, OF WILLIAMSTOWN, NEW YORK.

TEMPORARY REPAIR DEVICE FOR WAGON-THILLS.

No. 860,854.

Specification of Letters Patent.

Patented July 23, 1907.

Application filed February 11, 1907. Serial No. 356,781.

To all whom it may concern:

Be it known that I, EMERICK W. CRISPELL, of Williamstown, in the county of Oswego, in the State of New York, have invented new and useful Improvements in 5 Temporary Repair Devices for Wagon-Thills, of which the following, taken in connection with the accompanying drawings, is a full, clear, and exact description.

This invention relates to certain improvements in 10 temporary repair devices for vehicle thills in which a bendable strap of iron of suitable length is adapted to be applied to the broken parts of the thill and clamped thereto in such manner that the broken or separated parts may be temporarily united and drawn together 15 and used in such condition for an indefinite period of time, or until the broken parts may be conveniently replaced.

My object, therefore, is to provide a simple, practical and efficient thill repairing device capable of being 20 carried in the vehicle and readily applied to re-unite the broken parts, or at least to temporarily bind them together until suitable repairs can be made.

Another object is to enable the broken parts to be drawn together and rigidly clamped, and at the same 25 time to utilize the same repair-mechanism for coupling the thills to the shaft in case of breakage of the thill coupling.

Other objects and uses will appear in the following 30 description.

In the drawings, Figure 1 is a side elevation of a 35 broken thill with my improved repairing device applied thereto. Fig. 2 is a similar view of portion of the thills and axle, with my improved repair device as coupling the thills to the axle in the place of a broken 40 thill coupling. Fig. 3 is a perspective view of the detached strap and clip swivel connected thereto. Fig. 4 is a perspective view of the detached adjustable clip. Fig. 5 is a similar view of what may be termed the central clip, or that which is adapted to be applied to the 45 break.

This thill repairing device consists essentially of a 50 comparatively long and narrow, but thin strip —1— of bendable metal, such as malleable iron, or thin spring metal terminating at one end in a threaded stem or bolt —2—, and at its opposite end in a suitable eye —3— for receiving an eye-bolt —4— which is swiveled to the central portion of a clip —5— so that the latter may be turned upon the bolt —4—, and together with the part —4—, swung upon the adjacent end or eye —3— of the 55 strap —1— to any desired position or angle with reference to the strap —1—.

Mounted upon and adjustable lengthwise of the 60 threaded end or bolt —2— of the strap —1— is a second clip —6— having an apertured hub —7— for receiving the threaded portion —2—, which latter is provided 65 with an adjusting nut —8— adapted to engage the hub

—7— for drawing the parts to be coupled together when the clips —5— and —6— are clamped to such parts by their respective clamping bolts, as —9— and —10—. These clips —5— and —6— are adapted to be clamped 60 to the parts to be coupled at opposite sides or ends of the break, as for instance, in Fig. 1, I have shown the thill as split or broken at —a— leaving the two parts —t— and —t'— to be coupled together, and in this particular instance, I have shown the clip —5— as clamped to the 65 part —t— while the clip —6— is clamped to the part —t'—, and when these clips are so clamped, with the bar or strap —1— extending across the break and resting against the thill, it is evident that by adjusting the nut —8— the thill sections —t— and —t'— may be drawn 70 firmly together at the break —a— and in order that the broken ends may be more firmly bound together, I provide a third clip —11— which is fitted around the broken ends and is adjustable lengthwise of the strap —1— so as to be clamped at the desired part of the 75 break which is effected by means of a clip plate —12— and nuts —13— for drawing the clip-plate and clip firmly against the thill and strap.

In Fig. 2 I have shown my device as applied to the thill and front axle to take the place of a broken thill 80 coupling, in which case the clip —5— is clamped upon the axle, as —A—, while the strap —1—, which is hinged to said clip, is extended along one side, in this instance, the under-side of the thill and is firmly clamped to said thill by the clips —6— and —11—, the 85 clip —11— being in this instance, clamped near the coupling end of the thill and strap to prevent undue relative movement of the free end of the thill with reference to the strap. It will be seen that in this last instance the strap —1— is bent to conform to the curvature of the thill so that the thill and strap lie close together and are held in this position by the clips —11— and —6—. If it becomes necessary to draw the thill in closer relation to the axle, it may be readily done by 90 simply loosening the clip —11— and adjusting the 95 nut —8— against the clip —6— whereby the thill will be forced lengthwise of the strap toward the axle and may afterward be held in place by tightening the clip —11—.

It will be seen from the foregoing description that 100 this whole repair device is particularly simple; is readily adjustable to conform to the shape and position of the parts to be coupled, and when not in use, may be stored within a minimum space under the seat or in any other part of the vehicle ready for use.

105

What I claim is:

1. In a thill repair device, a metal strap threaded at 110 one end and having a nut adjustable thereon, a clip adjustably mounted upon the threaded end of the strap and adapted to be adjusted by said nut, a second clip swivel-connected to the opposite end of the strap, and an intermediate clip adjustable lengthwise of the central portion of the strap.

2. A device for temporary coupling broken parts of the
thill consisting of a strap of bendable metal, a clip ad-
justably secured to one end of the strap, a second clip
hinged to the opposite end of the strap and an inter-
mediate clip adjustable along the strap between the first
and second-named clip.
3. A repair device of the class described, said device
comprising a strap of metal having one end threaded and
provided with a nut, a clip mounted on said threaded end
10 and adapted to be adjusted lengthwise of the strap by
said nut, a second clip swivel connected to the opposite

ends of the strap and a third clip adjustable along the
central portion of the strap, said clips each consisting of
a U-shape plate and a clamping bolt for drawing the
opposite arms of the plate into firm contact with the parts 15
to be coupled.

In witness whereof I have hereunto set my hand this
30th day of January, 1907.
